UNITED STATES PATENT OFFICE

DANIEL C. HUNTERFORD, OF CORNING, NEW YORK

DOOR

Application filed December 28, 1928. Serial No. 329,052.

This invention relates to the art of buildings and, more particularly, to an improved door construction.

It is an object of this invention to provide a new and improved door construction.

It is another object of this invention to provide a door composed of a plurality of similar hinged sections which are independently supported at their upper ends.

10 It is a further object of this invention to provide a light weight inexpensive door which can be easily opened or closed by sliding it around the corner.

15 It is a still further object of this invention to provide a door composed of a plurality of sections which are movable with respect to one another and which are lapped to form tight joints between the individual sections.

20 It is also an object of this invention to provide a door construction which has means for overcoming wind resistance to opening.

It is still another object of this invention to provide door sections equipped with window sash.

25 With the above and other objects in view, which will be apparent as the description proceeds, I have set forth my invention in the following specification and have illustrated it in the accompanying drawings, in which:

30 Fig. 1 is a fragmentary plan view, with the roof removed, of a portion of an air-plane hangar provided with my new and improved door;

35 Fig. 2 is an inside elevation corresponding to Fig. 1;

Fig. 3 is a rear elevation, on a slightly smaller scale, of two adjacent sections embodying my invention;

40 Fig. 4 is a horizontal section on an enlarged scale, on the line 4—4 of Fig. 3, showing the interior construction of the individual sections, the lap between sections, the hinge construction, and the window construction;

45 Fig. 5 is a vertical transverse section, on the line 5—5 of Fig. 3, showing the overhead suspension, the means for closing the tops of the sections, the means for adjusting the height of the individual sections, and the wind thrust roller;

Fig. 6 is a vertical longitudinal section on the line 6—6 of Fig. 5;

Fig. 7 is a vertical transverse section, on the line 7—7 of Fig. 3, showing the means for closing the bottoms of the sections, the bottom guide construction, and the shield therefor;

Fig. 8 is an inside elevation corresponding to Fig. 7, and also showing the hinge construction;

Fig. 9 is a plan view of the curved track for guiding my door around the corner;

Fig. 10 is a vertical transverse section, on the line 10—10 of Fig. 9, showing the interior construction of the curved track and one of the means for guiding the cable around the corner; and Fig. 11 is a horizontal section on the line 11—11 of Fig. 3, showing the details of applicant's channels.

In the accompanying drawings, and referring particularly to Figs. 1 and 2, 10 designates a hangar provided with a stationary side wall 11 and a movable door 12 which, either separately or in conjunction with a second door, forms a closure for one side of the hangar 10. The walls which are not shown may be stationary or movable, and the stationary walls may be of any suitable type as they form no part of the present invention.

The door 12 comprises a plurality of substantially similar sections 13, which are secured to one another by hinges 14 and are supported by overhead rollers 15 that engage a track 16 carried by any suitable framework, such as the I-beams 17 and truss members 18.

Referring particularly to Figs. 3—8, it will be seen that the individual sections 13 each consist of a pair of similar reversely-arranged U-shaped channels 21 and 22 which terminate in laterally-extending flanges 23 and 24, preferably of unequal width. To assemble the sections one channel 21 is reversed with respect to a corresponding channel 22 so as to bring into engagement the corresponding flanges 23 and 24 of adjacent channels, whereupon these are securely fastened together, as by spot welding. A top closure plate 25 is secured in place a short distance below the upper ends of the channels 21 and 22, and a corresponding bottom clo-

sure plate 26 is secured at the bottom ends of the channels, preferably at their extreme ends. The plates 25 and 26 may be fastened to the channels in various ways, but I prefer to do this by arc welding 27. This forms a completely enclosed dead air insulating space 28 within each of the sections 13. The upper end of each of the sections 22 is also provided with a cut away portion 29 for a purpose to be described later.

The sections 13 are preferably attached to one another by hinges 14 which consist of hinge members 31 and 32 that are secured to the flanges 23 and 24, respectively, of adjacent sections, and are secured to one another by hinge pins 33, as best shown in Fig. 8. The hinge pins are made longer than the hinge members 31 and 32 to insure proper positioning of the latter over an appreciable range of vertical adjustment of adjacent sections. I prefer to secure the hinges to the flanges by spot welding, although other means may be used if desired. I also prefer to mount the hinges on the rear side of the door. As shown in Fig. 4, the combined thickness of the flanges and hinges is very small in proportion to the thickness of the sections, thus providing ample freedom of turning movement when the door is opened or closed around the corner as described below.

It is a special feature of my invention that the flanges on one section overlap the flanges on the adjacent sections, thus providing tight joints between adjacent sections and preventing the direct passage of air or the elements therethrough.

As shown in Figs. 1, 5, and 6, the individual sections 13 are each provided with a plurality of overhead rollers 15, of which four are shown herein. These are preferably mounted in pairs on studs 34 carried by yokes 35, whose opposite ends are mounted in interlocking relation on a supporting yoke 36 and held thereon by a nut 37. Yoke 36 preferably terminates in a hollow enlargement 38 in which is mounted a bolt 39 that is secured to the top closure plate 25. I prefer to do this by a nut 40 welded to the under side of the top closure plate 25 prior to its assembly with the channels 21 and 22, and to retain the bolt 39 in adjusted position by a lock nut 49. The bolt 39 is preferably attached to the center of the plate 25 so that the weight of the door section tends to hold it in a vertical position. As a result of this mounting it will be obvious that each section 13 may be raised or lowered with respect to the position of the rollers 15 by loosening the lock nut 49, and turning the bolt 39 in the required direction, that is, clockwise to raise the section and counter-clockwise to lower the section, after which the lock nut 49 is turned up to secure the section in the adjusted position. The cut away portion 29

in each section 22 permits the insertion of a wrench to effect this adjustment.

The track 16 is preferably closed on its top 41 and sides 42 but its bottom 43 is provided with a central slot 44, and for this purpose the bottom is slit longitudinally and the adjacent portions are turned inwardly to form guides 45 for the yoke 36 of the roller mechanism. The space between each in-turned portion 45 and the corresponding side wall 42 forms a guideway 46 for the corresponding roller 15.

One of the obstacles which normally renders large exterior doors difficult to slide is the wind resistance, and I have devised a simple means of overcoming this, which consists in the provision of a wind thrust roller 47 for each of the supporting yokes 36. While this roller may take various forms, I prefer to use a sleeve 47 which is telescoped over the yoke 36 prior to mounting the yokes 35 thereon. The roller 47 is retained in the proper position on yoke 36 in any desired manner, as by a shoulder 48 formed integrally with the yoke, or a collar mounted thereon.

The bottom of the door is preferably guided in its opening and closing movements by a curved T-shaped guide track 54, which is secured to the foundation or floor 55 of the hangar in any convenient manner, and the bottom of each door section 13 is preferably provided with a pair of antifriction rollers 56 which depend from a supporting plate 57 secured to the bottom closure plate 26 in any convenient manner, as by a bolt 58.

As shown in Figs. 7 and 8, the bottom of each door section 13 is preferably provided with a flap 60, which may be of any suitable material, such as canvas or rubber, to protect the bottom guide construction from the elements and to make a tighter fit for the bottom of the door. The flap 60 may be attached to the door sections in any convenient manner, as by the bolts 61, and is preferably a continuous member.

For the purpose of providing a convenient means for opening and closing the door I prefer to attach cables 62 and 63 to the extreme door sections, and this is preferably done by connecting the cables to the studs 34 of the roller mechanism. The cable 62 from the center door section, in the case of a double door, runs through the track 16, to a pulley mechanism 64, located in the center of the door opening, where it is reversed, passes to the corner of the building outside of the track, and is there turned substantially parallel to the side wall 11 of the building by one or more pulleys 65, carried by the track or track support. This end of the cable 62 then goes to an operating mechanism 66, which may be of any desired type and either hand driven, as shown, or provided with a suitable electric drive (not shown) if desired.

The other cable 63 is attached to the extrerie door section and, passing through the track 16, is attached to the operating mechanism 66. For a building provided with only one door in a side the mounting of the cable mechanism differs from that just described merely by arranging the pulley mechanism 64 at the opposite side of the building instead of in the center of the door opening.

5 To prevent binding between the cables 62 and 63 and the track 16, as the cables pass around the corner of the building, I prefer to provide a non-translatory antifriction mechanism. As shown herein, and particu-
 10 larly in Figs. 9 and 10, this may conveniently consist of a series of antifriction rollers 67, mounted on trunnions 68 in bearing plates 69 carried by the track 16. As shown, the cables slide against the rollers 67 and binding is
 15 avoided.

10 As best shown in Figs. 3, 4, and 5, any of the sections 13 may, if desired, be provided with window sash 70. These may be of any desired type but a suitable type is one provided with a metal framework 71 or 72 that has openings to receive panes of glass 73, which are secured thereto by retaining strips 74 bolted to the framework. The sash 70 may be secured to the door sections 13 in any desired way, as by spot welding. Likewise, the sash may be provided with double panes of glass, as in framework 71, or with single panes as in framework 72. I prefer to make the sash framework out of angle iron having a central body portion 75, which forms the window casing, and flanges 76 and 77 turned at right angles to the body portion and in opposite directions therefrom, as the flanges 76 form effective retaining means to hold the framework in position in the section 13 and the flanges 77 form a convenient support for the glass pane 73. The framework may be formed from similar angle iron portions, as in framework 71, or from angle irons 20 whose body portions 75 are of unequal length, as in framework 72. In practice the parts of the framework are inserted from opposite sides of the section 13 and spot welded, after which the glass is inserted.

25 50 In cases where it is not desired to have the door open around the corner the hinges 14 may be replaced by spot welds (not shown), thus forming a rigid door construction.

55 While my door may be made of any desired material, I have found a copper bearing steel well adapted for the purpose. The channels 21 and 22 may be made of any desired width or length, and of any desired gauge, such as 14, 16, 18, or 20 gauge.

60 65 It will be apparent that I have devised a door construction which may be made in any desired size and which is simple in construction, of light weight, is easily assembled, and will form a strong, tight, insulated door that can easily be opened or closed by moving the

cables in the desired direction. It will also be apparent that my new and improved door construction is independent of the regularity of the foundation, and that settling of the latter or excessive wind resistance will not affect its easy and rapid operation.

70 As many apparently widely different embodiments of this invention may be made without departing from the spirit and scope thereof, it is to be understood that I do not limit myself to the specific embodiments thereof except as defined in the appended patent claims.

I claim:

1. A door section which comprises a pair 80 of reversed U-shaped flanged channels welded together along their contacting flanges, and closure plates wholly confined between the ends of the channels and welded thereto.

2. A sliding door which comprises a plurality of hinged sections, each of said sections comprising a pair of reversed U-shaped channels having at their terminals outwardly extending flanges which support the hinges, the flanges being united along their 85 contacting portions.

3. A non-folding sliding door which comprises a plurality of similar and similarly arranged lapped hollow sections hinged together each of said sections comprising a 90 pair of reversed U-shaped channels having outwardly extending flanges secured together along their contacting portions.

4. The door of claim 2, in which each of 100 said sections is provided with overhead supporting means.

5. A sliding door which comprises a plurality of similar sections, means for independently supporting each of said sections centrally from an overhead track, means for independently adjusting said sections, and means for preventing the passage of air through said door in the vicinity of said adjusting means.

6. In a door construction, the combination 110 of a plurality of relatively adjustable door sections provided with overlapping flanges, the overlap being arranged on the same side of each door section cooperating relatively adjustable hinge sections welded to each section, and pins passing through the adjacent hinge sections and securing the door sections together.

7. In a door construction, the combination 115 of a plurality of sections, relatively movable hinge members for securing said sections to one another, an overhead support for said sections, and centrally disposed means on each section for independently adjusting the height of each section.

8. In a door construction, the combination 120 of a plurality of sections, means for securing said sections to one another, an overhead slotted track to support said sections, centrally disposed door supporting means carried 130

by each section passing thru said slot and engaging said track and a roller mounted on each of the individual door supporting means where it passes thru said slot for counteracting the wind tendency to cause binding between the sections and the support.

9. In a door construction, the combination of a plurality of independently adjustable sections, means for independently adjusting each section cooperating hinge members secured to opposite sides of the sections, and pins for securing adjacent hinge members together during the adjusting of said sections, said hinge members being cut away on adjacent edges to permit independent end-wise movement.

10. In a door construction, the combination of a plurality of sections, means for securing said sections to one another, overhead support for said sections, a vertical guide for the bottom of the door, and a pair of laterally engaging rollers associated with each section for cooperating with opposite sides of said guide.

11. In a door construction, the combination of a plurality of sections, means for securing said sections to one another, overhead support of said sections, and a roller arranged in a vertical plane passing through the longitudinal central portion of each door section to counteract the wind tendency to cause binding between the sections and the support.

12. In a door construction, the combination of a plurality of sections, means for securing said sections to one another, overhead support for said sections, including a track, a series of rollers cooperating with said track, and a series of connecting links between said rollers and said sections, and a roller mounted on each link for cooperation with said track for counteracting the wind tendency to cause binding between the sections and the support.

13. In testimony whereof, I affix my signature.
DANIEL C. HUNGERFORD.
